T. R. ARDEN.

TOY CANNON.

APPLICATION FILED MAY 23, 1917.

1,270,764.

Patented July 2, 1918.

UNITED STATES PATENT OFFICE.

THOMAS RAYMOND ARDEN, OF NEW YORK, N. Y., ASSIGNOR TO T. R. ARDEN CO., INC., OF NEW YORK, N. Y., A CORPORATION OF NEW YORK.

TOY CANNON.

1,270,764.

Specification of Letters Patent.

Patented July 2, 1918.

Application filed May 23, 1917. Serial No. 170,384.

To all whom it may concern:

Be it known that I, THOMAS RAYMOND ARDEN, a citizen of the United States of America, residing at New York city, in the county and State of New York, have invented certain new and useful Improvements in Toy Cannons, of which the following is a specification.

My invention relates to a toy cannon of the type adapted for ejecting balls or other objects by means of a spring actuated plunger.

The object of the invention is to provide a simply constructed and efficiently operating toy capable of being produced at a relatively low cost and so constructed as to reduce to a minimum the likelihood of any of the parts becoming broken or the device as a whole being disorganized when used by a child.

The invention consists of the construction and combination of parts hereinafter fully described and illustrated in the accompanying drawing, wherein—

25 Figure 1 is a top plan view of my improved toy cannon;

Fig. 2 is a longitudinal sectional view on the line 2—2 of Fig. 1; and

30 Fig. 3 is a vertical sectional view on the line 3—3 of Fig. 2.

The cannon shown in the drawing is mounted upon a carriage comprising the wheels 10 and the lateral arms 11 which constitute the frame.

35 Supported by the frame 11 is the barrel 12 which is preferably provided near its muzzle with an opening 13 to receive the objects to be shot from the cannon. In the form of invention shown in the drawing 40 balls 14 are employed, and adjacent the opening 13 the barrel is provided with a socket 15 into which a chute 16 may be removably inserted, the chute 16 being supported in an inclined position so that the 45 balls 14, which are placed in the chute, may roll into the barrel 12 through the opening 13 by gravity.

50 Mounted in the rear portion or breech of the barrel is a rod 17 projecting through a suitable longitudinal bore in such breech, the rear part of the rod 17 being formed as a crank 18 to receive the operating handle 19. The forward end of the rod 17 is formed as an open spiral 20, and encircling an intermediate portion of the rod 17

which is within the barrel 12 is a coiled spring 21. This coiled spring is confined between a collar 22 intermediate the ends of the rod 17 and the forward spirally twisted portion 20 of said rod 17. 60

Reciprocable within the barrel 12 is a plunger 23, said plunger being provided with a cross pin 24. Engaging the cross pin 24 is a hooked arm 25 of a link 26, said link having a second hooked arm 27 65 which reaches into engagement with the forward or spirally twisted portion 20 of the rod 17. The barrel 12 is provided with suitable slots 28 and 29 to allow for the to and fro movement of the link 26. 70

I may provide on the rod 17 adjacent the forward face of the breech a sleeve like ratchet 30 coöperable with a bar 31 held in a hub 32 surrounding a portion of shaft 33 on which the wheels 10 are mounted. This 75 ratchet 30 serves the double function of a ratchet and a noise maker when the crank 18 is turned.

The operation of the device is as follows:—A suitable number of balls 14 are 80 placed in the chute 16. Thereafter the crank 18 is turned by means of the handle. As a consequence of turning the crank the spiral 20 will retract the link 26 and its attached plunger 23 in the barrel 12 until the hooked 85 end 27 of the link 26 escapes from below the free end of the spiral portion 20. During the retraction of the link 26 the spring 21 is compressed by the rearward movement of the hooked arm 27. When the hooked 90 end 27 escapes from engagement with the spiral 20 the spring 21 is released and extends sharply whereby the plunger 23 snaps forward in the barrel 12 and expels a ball 95 14 in its path with considerable velocity. During rotation of the crank 18 the teeth of the ratchet 30 glide over the upper end of the bar 31 making a grating noise, at the same time preventing back throw of 100 crank 18.

It is to be noted that the ratchet 30 may be omitted if desired and the bar 31 may also be omitted, in which event the collar 22 would be moved farther back on the rod 17, preferably immediately adjacent the front 105 face of the breech.

What I claim as new and desire to secure by Letters Patent is:—

1. In a toy cannon, the combination of a barrel, a plunger reciprocable therein, ro- 110

tary spiral means for retracting said plunger in the barrel, and extensible means for protracting the plunger in the barrel.

2. In a toy cannon, the combination of a barrel, a plunger reciprocable therein, rotary spiral means for retracting said plunger in the barrel, a connection between said plunger and said rotary means, and extensible means for protracting the plunger in the barrel.

3. In a toy cannon, the combination of a barrel, a plunger reciprocable therein, a rod having a spiral portion mounted for rotation in said barrel, a connection between said plunger and said rod whereby when the latter is rotated the plunger is retracted in the barrel, and means for protracting the plunger in the barrel.

4. In a toy cannon, the combination of a barrel, a plunger reciprocable therein, a rod rotatably mounted in said barrel and having one end formed as a spiral, a link connecting said plunger with said rod, and a coiled spring for protracting the plunger in the barrel.

5. In a toy cannon, the combination of a barrel, a plunger reciprocable therein, a rod rotatably mounted in said barrel and having one end formed as a spiral, a link having its opposite ends hooked, one of said ends engaging the plunger and the other reaching into engagement with the spiral part of the rod, and a coiled spring surrounding said rod and in the path of the last named hooked end of the link.

6. In a toy cannon, the combination of a barrel, a plunger reciprocable therein, a rod mounted for rotation in said barrel, a connection between said plunger and said rod whereby when the latter is rotated the plunger is retracted in the barrel, means for protracting the plunger in the barrel, a ratchet on said rod, and a pawl extending into engagement with said ratchet.

In testimony whereof I have affixed my signature in presence of two witnesses.

THOMAS RAYMOND ARDEN.
